UNITED STATES PATENT OFFICE.

JOEL WEIGEL, OF PITTSBURG, CALIFORNIA.

COMBINED HINGE AND LADDER FOR SILOS.

1,158,756.

Specification of Letters Patent.

Patented Nov. 2, 1915.

Application filed March 2, 1915. Serial No. 11,537.

To all whom it may concern:

Be it known that I, JOEL WEIGEL, a citizen of the United States, residing at Pittsburg, in the county of Contra Costa, and State of California, have invented new and useful Improvements in Combined Hinges and Ladders for Silos, of which the following is a specification.

This invention relates to a mounting for 10 silo doors and pertains especially to a combined door and ladder.

The particular purposes of the invention are to provide an outside fastener for a silo door, whereby it may be firmly seated 15 in the jamb at all its corners; to provide a fastener by which the door may be bodily shifted laterally inwardly away from the jamb and then swung through an arc in a plane close to the inner surface of the silo 20 wall.

A further object is to provide a mounting for locking, operating and supporting the door and which also forms, when superposed as in silo construction a rung useful 25 as a ladder whereby access may be had to the higher doors.

The invention consists of the parts and the combination and construction of parts 30 as hereinafter more fully described and claimed, having reference to the accompanying drawings, in which—

Figure 1 is a side elevation of a portion of a silo wall and showing one door closed and locked, and a higher one in opening 35 position. Fig. 2 is a horizontal section showing a door fully open. Fig. 3 is a vertical section showing a door in edge view closed and locked, and one of its locking arms free. Fig. 4 is a perspective of a detached clamp. Fig. 5 is a similar view of a 40 door mounting and operating means.

2 indicates a portion of the curved wall of a silo with jamb or post members 3 and horizontal sills 4, these latter being rabbed to form doorways 5, vertically superposed.

Each doorway 5 is provided with a door 6 and it is one of the important objects of this invention to provide a mounting where- 50 by the door may be tightly drawn against its seat. To that end each door is pivoted at 7—7 upon the end of crank arms 8—8, whose shafts 9—9 are pivoted in bearings fastened on the outside of one of the jambs 3. The outer end of each shaft 9 has an

eye 10 through which is slidable a lever 11 forming a handle whereby the crank shaft may be rotated and thus raise or lower the door through an arc, as in Fig. 1.

In the present embodiment each door is 60 provided with parallel Z bars 12 bolted at 13, and forming below the lower flanges a space 14 in which the crank arms 8—8 lie when the door is either fully open, Fig. 2, or fully closed, Fig. 3.

The bars 12 form substantial braces for the doors and as the bolts 13 pass through the upper flange of the Z bar their nuts are approximately flush with the offset lower flange and therefore form no obstruction to the movement of the door.

The crank shaft bearing comprises an inner U-shaped strap 15 set edgewise against the jamb face and having oppositely directed, spaced lugs 16. The bent end of the 75 strap 15 is set to project beyond the edge of its jamb and receive the shaft 9, Fig. 2, and is clamped down by a piece of channel-iron 17 forming a cap through which pass fastening bolts 18.

By providing a pair of operating cranks 8—8, to each door, on one side or jamb of the doorway, the door may be swung up or down with its sides in vertical positions. On the opposite jamb 3 is also a set of 85 bearings 15 in which are turnable lock shafts 20, each with an arm 21 turnable to enter the space 14 of the brace bar 12 when the door 6 is in juxtaposition therewith. The outer end of the lock shaft is provided 90 with an eye 22 in which is slidable a handle or lever 23.

The handle or lever 23 and the arm 21 lie in the same plane at opposite ends of their shaft 20, as also do the arms 8—8 and levers 95 11—11 of shafts 9—9. The crank shafts 9 and the lock shafts 20 are sufficiently long to push the door 6 back from the jamb and to permit it to be thus turned upwardly in an arc and swung edgewise close to the inner surface of the silo wall Fig. 2.

The crank shaft handle 11 has at one end a sleeve or socket 24 and when the door is closed the horizontal handle 23 of shaft 20 can be shifted across the front of the door 105 11, Fig. 1.

When the door is closed it is firmly seated in the rabbets by means which force the several shafts 9—20 outward and thus pull on 110

the door. The locking means is as follows: Each handle 11-23 is provided with a threaded eye 25 in which is a threaded rod 26 having an end 27 bent in a curve which is 5 eccentric to the axis of its handle bar. Thus, when the door is closed and drawn forward and the handles 11-23 alined and joined at the socket 24, then the rods 26 are so turned that the curved ends 27 abut 10 the caps 17 of the bearing. Owing to the eccentricity of the end of the arm it acts cam-fashion and forces the shaft 8 or 20 outward. Therefore, it will be seen that I have provided means whereby each corner 15 of the door is drawn snugly up against the jamb. The alined and inter-related handle members 11-23 of the superposed, closed doors thus assume positions in a common vertical plane and form a substantial 20 ladder, the handle members becoming rungs thereof. The locking rods 26 when forced into abutment with the coördinate bearing cap also form a brace, of which there is one at each end of the rung-forming members. 25

25 The curved or cam ends of the locking rods bear on the caps 17 close to an adjacent bolt 18 and are thereby prevented from turning. The object of threading the lock rods 26 in the eyes 25 of the parts 11-23 is to 30 provide for the adjustment of the cams 27 toward or from the respective caps 17, as may be necessary.

An advantage provided by the peculiar bearing 15 is that by adjusting it toward or 35 from the edge of its jamb ample lateral play may be allowed the shaft therein for the adjusting of the door adjacent the curved wall of the silo.

Having thus described my invention what 40 I claim and desire to secure by Letters Patent is—

1. The combination with a wall having an opening or bearings, shafts shiftable axially in said bearings, transversely to the plane 45 of the opening, and rotatable in or parallel to the plane of the wall and having crank arms, a door connected to the crank arms and movable therewith edgewise by the crank arms and laterally by the said axial movement, and radial handle means whereby the shaft may be rotated, said handle means being rotatable on the radial axis and having means to move said shaft axially.

2. In combination, a wall provided with 55 an opening, a closure for the wall opening, bearings arranged on the wall adjacent to the opening therein, shafts slidable in the bearings for opening the closure and connected to the latter for supporting the same, 60 and means directly on the shafts for locking the latter from sliding and thereby the closure in operative position.

3. The combination with a wall having an 65 opening and a door for the opening and closable outwardly against its jambs and top

and bottom, of a plurality of rotatably and slidably mounted shafts on the wall on the opposite sides of the opening therein and engageable with the door, a pair of which on one side of the wall opening is connected to 70 the door for supporting the latter whereby it may be moved to cover or uncover the opening, and the shafts on the opposite side of the wall opening engaging with door when in closed position to lock the same 75 closed.

4. The combination with a wall having an opening and a door for the opening and closable outwardly against its jambs and top and bottom, of a plurality of rotatably and 80 slidably mounted shafts on the wall on the opposite sides of the opening therein and engageable with the door, the shafts on one side of the wall opening being connected to the door and supporting the same whereby it 85 may be moved to cover or uncover the opening, and the shafts on the opposite side of the wall opening being adapted to engage with the door to lock it closed, and means for firmly seating the door in closed position. 90

5. The combination with a wall having an opening and a door for the opening and closable outwardly against its jambs and top and bottom, bearings on the walls, of a plurality of shafts slideable in the bearings on 95 the wall and engageable with the door, certain of said shafts being connected to the door and supporting the same for movement to cover or uncover the opening, and means operative upon said shafts for firmly seating 100 the door in closed position, said means comprising rods connected to the shafts and reacting against coördinate parts.

6. The combination with a wall having an opening and a door for the opening and 105 closable outwardly against its jambs and top and bottom, of a plurality of shafts on the wall and engageable with the door, a pair of which on one side of the wall is connected to the door and whereby it may be 110 moved to cover or uncover the opening, and handle bars for the shafts whereby they may be actuated, said handle bars being co-operative in pairs whereby each pair constitutes an individual rung useful as a 115 ladder.

7. The combination with a wall having an opening and a door for the opening and closable outwardly against its jambs and top and bottom, of a plurality of shafts slidably 120 mounted on the wall and engageable with the door, a pair of which on one side of the wall is connected to the door and whereby it may be moved to cover or uncover the opening, handle bars for the shafts whereby they may be actuated, said handle bars being co-operative in pairs to form individual rungs useful as a ladder, and adjustable locking rods connected to said handle bars 125 and adapted, when moved to an operative 130

position, to slide the shafts so as to firmly seat the door in closed position.

8. In combination with a wall provided with an opening, of a closure for the opening in the wall, a bearing disposed on the wall, and a shaft slideable and rotatable in the bearing and connected to the closure for supporting the closure.

9. A structure of the character described comprising, in combination, a wall having an opening, bearings on the wall, a closure for the wall opening, a plurality of shafts slideable in the bearings and connected to the closure for supporting the latter, and means on the shafts for locking the latter from sliding and the closure in operative position.

10. A structure of the character described comprising, in combination, a wall having an opening, a bearing on the wall, a closure for the wall opening, and a crank shaft slideable and rotatable in the bearing and having its arm connected to and supporting the closure for movement.

11. A structure of the character described comprising, in combination, a wall having an opening, a bearing on the wall, a closure for the wall opening, a crank shaft slideable and rotatable in the bearing and having its crank arm connected to and supporting the closure for movement, and lock means on the shaft locking the latter from sliding and rotating and for retaining the closure in operative position.

12. A structure of the character described comprising, in combination, a wall having an opening, a bearing on the wall, a closure for the wall opening, a crank shaft slideably and rotatably disposed in the bearing and supporting the closure for movement, and cam means on the shaft adapted to bear against the wall for locking the shaft against movement.

13. A structure of the character described comprising, in combination, a wall having an opening, a bearing on the wall, a closure for the wall opening, a crank shaft slideably and rotatably disposed in the bearing and supporting the closure for movement, a relatively movable handle carried by crank shaft for operating the latter, and a lock means adjustably carried on the handle for holding the shaft from movement.

14. A structure of the character described comprising, in combination, a wall having

an opening, bearings on the opposite sides of the opening of the wall, a closure for the wall opening, shafts mounted in the bearings for supporting the closure in an operative position, and operating handles carried by the shafts and adapted to interlock releasably with one another when the closure is operative.

15. A structure of the character described comprising, in combination, a wall having an opening, bearings on the opposite sides of the opening of the wall, a closure for the wall opening, shafts mounted in the bearings for supporting the closure, and handles slidably carried by the shafts, one of said handles having a socket to receive the adjacent end portion of the other handle to interlock the handles.

16. A structure of the character described comprising, in combination, a wall having an opening, bearings on the opposite sides of the opening of the wall, a closure for the wall opening, shafts mounted in the bearings for supporting the closure, handles for the shafts adapted to interlock with one another, and means for locking the handles in interlocked relation.

17. A structure of the class described comprising a wall formed with an opening, a closure for the wall opening, bearings on the wall, shafts in certain of the bearings for supporting the closure for movement, other shafts in the other bearings adapted to engage with the closure when the latter is seated in the wall opening, said shafts being slideable axially in the bearings, and means for exerting an axial pull on the shafts to hold the closure seated.

18. A structure of the class described comprising a wall formed with an opening, a closure for the wall opening, bearings on the wall, a flanged member secured to the door and having its flange offset in spaced relation thereto, and crank shafts operable in the bearings and having arms adapted to engage beneath the offset flange of the aforesaid member.

In testimony whereof I have hereunto set my hand in the presence of two subscribing witnesses.

JOEL WEIGEL.
